UNITED STATES PATENT OFFICE.

ALVAH F. SPOONER, OF STERLING, ILLINOIS.

PUNCHING-MACHINE.

SPECIFICATION forming part of Letters Patent No. 289,577, dated December 4, 1883.

Application filed November 16, 1882. (No model.)

To all whom it may concern:

Be it known that I, ALVAH F. SPOONER, a citizen of the United States, residing at Sterling, in the county of Whiteside and State of Illinois, have invented certain new and useful Improvements in Punching-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to that class of machines used for punching holes in metal, wood, leather, or other material; and it consists, essentially, first, in a novel means of actuating the punch; second, in a novel method of actuating the feed by means of the punch; third, in an improved method of seating the punch; and, fourth, in a provision for indicating the number of holes punched.

20 In the drawings, Figure 1 is a side elevation of a machine embodying my invention. Fig. 2 is an end elevation. Fig. 3 is a detail view. Fig. 4 is a perspective view of the guideway to lead the material to be punched under the punch.

25 A are plates forming the sides of the machine, fastened together in any suitable manner, and furnishing the bearings for the crank-shaft D and rests for the punch bed-plate.

30 B is a punch-standard pivoted to the bed-plate C through the ears e, and having attached to its front side the punch-holder b, which latter is attached to such standard B by a set-screw, e, passing horizontally through a vertical slot in the punch-standard B into a threaded hole in the punch-holder b. In the horizontal projection s of the top of the punch-standard B, over the upper end of the punch-holder b, is seated a vertical set-screw, f, the lower end of which abutting against the upper end of the punch-holder b assists in holding the latter against the resistance of the material punched, and is used to adjust the punch vertically. In the punch-holder b is formed the round vertical hole t, into which 35 the shank-holder of the punch or punches h is

fitted, said holder being held in place by the horizontal set-screw g, which passes through the front wall of the hole t and abuts against the punch-shank holder. Where two or more punches are used, by placing their shanks in the proper position and securing them in place, as above described, the holes made by the punches may be punched longitudinally in the material punched, or diagonally, transversely, or in any intermediate position therein. The 40 punch-standard B, at a point immediately below the set-screw e in its upper projection, is divided into two arms, w, which pass backward on each side of the bed-plate C, and from its point of attachment to said plate C at 45 e, on the side nearest the operator, there extends downward and forward the arm v.

At g' is shown a feed-clamp pivoted to the side plate of the machine, between which clamp and the punch bed-plate C the material 50 to be punched is held in position while its forward part is under the punch h. The clamp is made to act with sufficient power for this purpose by the wire springs g', sprung between studs j' j'.

55 C is the punch bed-plate, having side projections or lugs, x x, which are seated in and traverse the horizontal slots x' x' in the sides A A. The bed-plate C is also provided with a depression, u, in its upper face, into which 60 wood, leather, lead, or other material is fitted for the punch h, when in operation, to cut against. Upon the lower central face of said bed-plate C is the bifurcated lug j, to which is pivoted one end of the arm k, the other end of 65 said arm k being provided with the oblong hook r, which engages the crank r' of the crank-shaft D, by which the machine is operated. The crank-shaft D serves the double purpose of reciprocating the bed-plate C, with the 70 punch-standard B thereto attached, and by the use of the cams y on the crank-shaft D also oscillates the punch-standard B. In one of the sides A is formed the horizontal slot E, and by means of a screw, f', there is held 75 against the outer side of such slot a clamp, f, and against the inner side of such slot the trip e', the latter serving the purpose of throwing up the punch-standard B by engaging the arm v and (as the forward movement of the punch- 80

head draws the material upon the bed-plate C) releasing such punch, thereby gaging the distances between the punched holes. By moving the screw f^2 forward or back in the 5 slot E the distances between the punched holes can be regulated as desired.

The method I have invented of regulating the number of holes to be punched at any time is as follows: On the forward leg of the side 10 nearest the operator I journal the ratchet-wheel H, which has in its periphery a series of one hundred ratchets and the tongue projection o, immediately below which, on the front face of the wheel H, is the lug n. A clamp, 15 p, with its single notch z, I attach to any desired part of the periphery of the wheel. The surface of the wheel H is divided into ten equal parts of ten ratchets each, the said divisions being indicated on the face of the wheel. Immediately under the upper part of the wheel 20 H and against the side A is screwed or riveted the T-shaped iron l, which moves on said screw or rivet, but not freely enough to change its position by its own weight. This T-shaped 25 iron has on its upper edge the semicircular projection m, immediately above which, and in the same plane therewith, is the pawl q, riveted loosely to the side A. Attached to one of the arms of the wheel H is one end of a coil-spring, 30 3, said spring being coiled around the axle of the wheel H, between said wheel and the side A, and having the other end attached to the side A.

The strip of leather or other material to 35 be punched is introduced under the feed-clamp g' and brought along beneath the guide consisting of the upper part, c', and the adjustable side piece, c'', under the punch h at the point for the first hole or set of holes. Then 40 by the turning of the crank-shaft D the cams y on said crank-shaft operating against the end of the arms w of the punch-standard B, the said standard working upon its pivot at e is thrown forward and downward, forcing 45 the punch h through the material to be punched. The pieces punched out will flow off down the chute b'. The punch remains in such position while the bed-plate C is drawn by the arm k and crank r' back to the point where the 50 forward arm, v, of the punch-standard B encounters the trip e', when such encounter tilts the standard, carrying its arms w downward, and raises the point of the arm v over the trip e', and thereby removes the punch from contact 55 with the material to be punched, such material having been drawn back by the punch h the proper interval between the holes punched. As the crank is further revolved, the bed-plate C and standard B are progressed 60 forward along the strap to be punched to the proper position for the next hole or set of holes. In its progress the point of the pawl d' engages one of the notches on the wheel H and pushes it forward one notch, and the point 65 of the pawl q holds said wheel in the position

in which it is left by the pawl d'. The operation is then continued until the desired number of holes are punched. When this result is reached, (the counting-wheel H having been properly set,) the clamp p is immediately in 70 front of the line of movement of the pawl d', which in such forward movement encounters the notch z on said clamp, and throws the forward end thereof against the T-shaped iron l, which in its turn revolves its projection m against the pawl q, and holds it from contact with the wheel H until the pawl d' moves back out of the notch z, when the spring 3, coming into action, reverses the movement of the wheel H. The lug n on the face of such wheel strikes 80 against the end of the T-shaped iron nearest to it and throws it back from its contact with the pawl q, the latter being knocked into position by the tooth o, and at the next movement of the punch the point of the pawl d' starts again to count at the cipher on the wheel. The wheel H is actuated and revolved one ratchet at each forward motion of the bed-plate C by means of the pawl d', pivoted to the side of such bed-plate, and which 85 engages the ratchets on the periphery of the wheel H.

What I claim as my invention, and desire to 90 secure by Letters Patent of the United States, is—

1. The machine-frame constructed of the side plates, A, suitably connected, the punch-standard B, reciprocating bed-plate C, arm or link k, and crank-shaft D, in combination, substantially as shown, and for the purpose 95 described.

2. The reciprocating bed-plate C, provided with the stud j, and arm k, having the hook r, in combination with the crank-shaft D, substantially as shown, and for the purpose specified. 105

3. The reciprocating bed-plate C, arm k, punch-standard B, and crank-shaft D, provided with the cams y y, in combination, substantially as shown, and for the purpose mentioned. 110

4. The punch-standard B, having the arms v and w, and the reciprocating bed-plate C, provided with the ears e, and the crank-shaft D, having cams y y, in combination, substantially as shown, and for the purpose described. 115

5. The reciprocating bed-plate C, punch-standard B, having arm i, rod k, crank-shaft D, and adjustable trip e', in combination, 120 whereby the distance between the punchings is regulated, substantially as shown, and for the purpose specified.

6. In a punching-machine, as described, the punch-head b, having a suitable hole or seat 125 for a punch, h, combined with said punch and a set-screw, whereby the punch may be set in any desired position relative to the material to be punched, so that holes can be made therein longitudinally, diagonally, transverse- 130

ly, or in any desired arrangement, substantially as described.

7. The ratchet-wheel H , provided with the projection o and lug n , in combination with the clamp p , having the notch z , iron l , having the projection m , the pawl q , and spring 3 , substantially as shown, and for the purpose herein named.

In testimony whereof I affix my signature in presence of two witnesses.

ALVAH F. SPOONER.
